UNITED STATES PATENT OFFICE.

WILLIAM S. FREEMAN, OF CHICAGO, ILLINOIS.

BURIAL-CRYPT.

1,053,488.

Specification of Letters Patent.

Patented Feb. 18, 1913.

Application filed July 28, 1912. Serial No. 712,107.

To all whom it may concern:

Be it known that I, WILLIAM S. FREEMAN, a citizen of the United States, residing at Chicago, in the county of Cook and State of Illinois, have invented a certain new and useful Improvement in Burial-Crypts, of which the following is a full, clear, concise, and exact description, reference being had to the accompanying drawings, forming a part of this specification.

My invention relates to burial crypts, and its object is to provide a simple, practical and inexpensive form of burial crypt; to provide for the proper ventilation of the same; to arrange for the disinfecting of the crypt and its various parts; and to accomplish the foregoing and other desirable results in a simple and expeditious manner.

In carrying out my invention I arrange to introduce in some convenient manner an antiseptic material into the crypt and preferably arrange for the circulation of air within the crypt or vaults thereof. This is conveniently done by circulating an antiseptic gas or air containing the same through the crypt or its vaults by suitable apparatus involving a circulating system with proper supply of antiseptic material.

In the accompanying drawing, the figure 30 is a vertical section of a burial crypt embodying my present invention.

In this figure I have shown a building 1, which is understood to represent any desired style or form of mausoleum or crypt, the 35 particular style or form of crypt not being any part of my invention, as the invention is applicable to any crypt. A door 2 is shown and a series of vaults or catacombs 3—3 arranged one above the other at one 40 side of the crypt. Doors or openings 4—4 are conveniently provided to allow access to the interior of the vaults 3—3. The rear wall 5 is separated from the building wall 6 so as to form an air space 7 between the 45 walls 5 and 6. I desirably arrange for the circulation of air and disinfecting material and for that purpose have shown as one desirable arrangement a circulatory system comprising a vertical exhaust pipe 8 having

branch pipes 9—9 conveniently communicating with the lower part of the rear end of each vault 3, together with a vertical supply pipe 10 having branch pipes 11—11 running through the floors 12 separating the vaults from one another. The exhaust pipe 55 8 is connected with an exhaust blower or other like apparatus 14 shown conveniently driven by an electric motor 15. The pipe 10 is connected with a tank or reservoir 16 containing suitable antiseptic material such as formaldehyde, or other desired antiseptic. Thus it will be seen the exhaust fan or blower 14 will cause a circulation through the several vaults by suction and the antiseptic material or gas will be drawn from the reservoir 16 up into and through the various vaults. Thus a circulation as continuous as desired will be produced resulting in a thorough withdrawal of the gases from the various vaults and disinfecting of the same.

It will be understood that changes and modifications can be made without departing from the spirit of the invention.

What I claim is:

1. A burial crypt having an inlet at or near its top, and an outlet at or near its bottom, in combination with means for introducing gas through the inlet and means for withdrawing the air and gases through the outlet.

2. In a burial crypt, the combination of vertically arranged inlet and outlet pipes and branch pipes extending respectively from the vertical inlet pipe to the top of one end of the crypt, and from the vertical outlet pipe to the bottom of the other end of the same.

3. In a burial crypt, the combination of vertically arranged inlet and outlet pipes and branch pipes extending respectively from the vertical inlet pipe to the top of one end of the crypt, and from the vertical outlet pipe to the bottom of the other end of the same, a device for supplying disinfectant material connected to said vertical inlet pipe, and an exhaust apparatus connecting with said vertical outlet pipe.

4. A burial crypt having vaults formed by vertical and horizontal walls, and a pipe extended through a vertical wall to communicate with one end of a vault, and another pipe extended lengthwise through the horizontal wall and communicating with the other end of the burial vault.

In witness whereof, I hereunto subscribe my name this 26th day of July, A. D., 1912.

WILLIAM S. FREEMAN.
